UNITED STATES PATENT OFFICE.

ISIDOR FARER, OF NEW YORK, N. Y., ASSIGNOR TO UNION SPECIAL MACHINE COMPANY,
OF CHICAGO, ILLINOIS, A CORPORATION OF ILLINOIS.

COMBINED FOLDER AND BINDER FOR SEWING-MACHINES.

1,281,924.

Specification of Letters Patent. Patented Oct. 15, 1918.

Application filed September 12, 1916. Serial No. 119,710.

To all whom it may concern:

Be it known that I, ISIDOR FARER, a citizen of the United States, residing at New York, in the county of Bronx, State of New York, have invented certain new and useful Improvements in Combined Folders and Binders for Sewing-Machines, of which the following is a description, reference being had to the accompanying drawing and to the figures of reference marked thereon.

My invention relates to new and useful improvements in sewing machines and more particularly to a combined folder and binder for guiding and binding the overlapped meeting edges of sections of fabric.

An object of the invention is to provide a sewing machine having a tubular work support and a folder for directing the edges of fabric sections which are to be joined to form a tubular article without folding the inner edge with a binder for directing a binding strip about the inner edge, so that said binding strip will be stitched by the needles joining the edges of the fabric sections.

A further object of the invention is to provide a combined folder and binder of the above character, wherein the folder is so mounted that it may be moved away from the binder to facilitate the insertion of the binding strip to the binder.

A further object of the invention is to provide a sewing machine for stitching tubular articles, with a folder and binder, which are so disposed relative to the stitching mechanism as to overlap and fold one only of the overlapped edges of a tubular article and bind the plain or unfolded edge of the overlapped edges.

A still further object of the invention is to provide a machine of the above character for folding and binding tubular articles, with a guide adapted to extend within the tubular article as it is stitched for guiding the binding strip to the binder.

These and other objects will in part be obvious, and will in part be hereinafter more fully disclosed.

In the drawings which show by way of illustration one embodiment of the invention:

Figure 1 is a side view of a sewing machine having my improvements applied thereto;

Fig. 2 is an end view of the same, with the cap of the machine removed, and also showing a tubular article being stitched;

Fig. 3 is a view partly in end elevation, and partly in section, showing the needles, the work support with the cap removed, the presser foot, the binder and the guide for directing the binding strip to the binder;

Fig. 4 is a view partly in plan and partly in section, showing the work support, the binder, the guide for the binding strip; also showing the fabric sections being stitched, said sections being broken away to show their relative arrangement;

Fig. 5 is a plan view of the work support, the presser foot, the folder, the binder and a portion of the binding strip guide;

Fig. 6 is a similar view showing the presser foot omitted and the folder withdrawn to facilitate the insertion of the binding strip;

Fig. 7 is a view showing more or less diagrammatically the needles, the work support and the overlapped edges of the fabric, one of which is folded and the other of which has been bound, a portion of the binder being shown in section;

Fig. 8 is a sectional view through the binder;

Fig. 9 is a front end view of the binder;

Fig. 10 is a sectional view showing the two edges of a fabric stitched and one edge only being bound by my improved mechanism;

Fig. 11 is a bottom plan view of the same; and

Fig. 12 is a detail sectional view, showing the manner of securing the slide to the extension.

The invention consists primarily in a stitching mechanism for stitching overlapped edges of fabric sections, which is preferably embodied in a machine having a tubular work support, so that a tubular article may be formed, such as a sleeve for a coat or the like.

Cooperating with the stitching mechanism is a feeding mechanism, which feeds the overlapped sections on to the work supporting arm for the stitching operation. Located in advance of the stitching mechanism is a combined folder and guide, which receives the edges of the fabric which is to be stitched into a tubular article. This

combined folder and guide is shaped so as to fold the upper overlapped edge of the fabric, while the lower edge is left plain or unfolded.

5 Directly in the rear of the combined folder and guide is a binder, which is preferably of the "English" binder type,—that is, a binder which folds the binding strip and then inverts the same as it is directed 10 to the stitching mechanism. This binder is disposed between the folder and the needles, and is so located relative to the guide as to direct the binding strip about the plain or unfolded edge, so that when the stitching 15 mechanism operates upon the fabric edges and the binding strip, one of the needles penetrates said fabric adjacent the fold in the upper edge thereof, and the other needle penetrates both fabric edges and adjacent the inner edges of the binding strip. 20

Also coöperating with the binder is a guide which extends parallel with the work-supporting arm, so that when a tubular article is being stitched the binding strip passing 25 through this guide to the binder will be led to the inner face of the tubular article and bind the plain or unfolded edge on the inner face of said tubular article.

Referring more in detail to the drawings, 30 I have shown my invention applied to a sewing machine consisting of a supporting bed 1 having a standard 2 carrying an overhanging arm 3. Also carried by the standard and projecting therefrom is a tubular work support 4. This tubular work support 35 projects underneath the free end of the overhanging arm. Located within the tubular work support is a feeding mechanism including a feed dog 5 (see Fig. 6), which is so disposed as to feed the material being 40 stitched lengthwise of the tubular work-supporting arm. The feeding mechanism is so constructed as to feed the material in the direction of the arrow Fig. 6, or onto the 45 work-supporting arm during the stitching operation. After the tubular article has been thus formed, it is withdrawn from the arm. This general type of machine and method of stitching tubular articles are well known 50 in the art, and further description thereof is not thought necessary.

In the forward end of the overhanging arm 3 is a needle bar 6, which carries two needles 7 and 8. The needle bar is reciprocated by a needle lever 9, connected to the needle bar by means of the link 10. Extending 55 through the standard 2 is a main shaft 11, provided with a belt wheel 12. On this main shaft is a suitable eccentric with which an eccentric strap 13 coöperates, and this eccentric strap engages a ball stud on the 60 end of the needle lever 9.

Also mounted in the overhanging arm is a presser bar 14, which carries a presser foot 65 15. The presser foot bears on the work-

supporting arm and coöperates with the feed dog 5 in the feeding of the fabric being stitched.

Coöperating with the needle 7 beneath the work support is a looper 16, while coöperating 70 with the needle 8 beneath the work support is a looper 17. These loopers are mounted on a looper-carrier 18, attached to a shaft extending lengthwise of the tubular work-supporting arm, and this shaft is actuated through suitable connections with the main shaft 11.

Directly in front of the stitching mechanism is a folder 19. Located between the folder 19 and the needles is a binder 20. 80 This binder is, as above noted, of the "English" binder type, and is adapted to receive the binding strip in a direction at right angles to the line of feed, invert the same and direct said inverted strip to the stitching mechanism. The binding strip is directed to the binder by a suitable binding strip guide 21, which extends parallel with the work-supporting arm 4, and to a point 85 in rear of the standard 2.

The throat plate 22 (see Fig. 4) is provided with a forwardly extending portion 23, which extends beyond the front end of the work-supporting arm. This extension has a recess adapted to receive a slide 24, 90 which carries a folder. The folder is secured to the slide by suitable screws 25 and the slide is secured to this extension by a screw 26' which passes down through a slot 26 extending lengthwise of the extension. 100 This slide 24 is formed with a thumb piece or handle, whereby it may be pushed toward the stitching mechanism, or drawn away from the same. When it is moved up toward the stitching mechanism, then the folder is 105 brought close to the binder for folding and guiding the edges of the fabric being stitched. When it is moved away from the binder, then the binder is exposed, so that the operator may readily direct the binding 110 strip therethrough.

The folder has a fabric-guiding portion 27 (see Fig. 2) and an edge guide 28 for the fabric section which passes over said guiding portion 27. Said folder is also provided 115 with a second fabric-guiding portion 29 for the other edge of the fabric section to be stitched. The section 29 carries a folding scroll 30, adapted to receive and fold the edge of the fabric section resting on the 120 fabric-guiding portion 29.

In Fig. 2 of the drawings, I have shown a tubular article indicated at F being guided and stitched. The edge f of the fabric rests upon the guiding portion 27 125 and is directed by the edge guide 28. This edge of the fabric is plain or unfolded. The other edge of the fabric indicated at f' is, however, bent back upon itself or folded as it is passed to the stitching mechanism. 130

This folder is so positioned that the needle 7 passes down through the folded edge adjacent the fold therein, as clearly shown in Figs. 7 and 10. In Fig. 10, the line *n* indicates the line of stitching formed by the needle 7.

The edge *f* of the fabric projects slightly beyond the folded-under edge *f'*. The binder is so disposed as to place a binding, indicated at B, about this projecting edge *f* of the fabric. This binder 20 is secured to a bracket 31 by screws 32 which pass through slots 33 in a second bracket 31^a connected to the binder 20. This permits the binder to be adjusted transversely of the line of feed.

The binder is formed with two guiding walls 34 and 35, thus making a U-shaped guiding space. The guiding wall 34 extends about the guiding wall 35 at the lower side thereof, so the lower edge of the binding strip will be folded back, as indicated at *b*. As the binding strip passes through this binder, it will be folded and the lower edge thereof will be turned back on the outer face of the binding strip. The end of the binder is cut away at an angle of 45 degrees, as is common in this type of binder, so this folded binding strip may be inverted to bring the folded back part between the side faces of the binding strip. The binder is so placed on the machine that when the binding strip is inverted and directed to the stitching mechanism, the needle 8 will pass through the edges of the binding strip. In Fig. 10 of the drawings, the line *n'* indicates the line of stitching formed by the needle 8, which passes down through the upper fabric and through the inner edges of the binding strip.

The binding strip guide 21 is in the form of a skeleton guiding frame which extends from a point adjacent the binder to a point at the rear of the machine, and this binding strip guide is secured to the machine by suitable brackets 37 and holding screws 38. The binder 20 is also provided with a guiding extension 39, for guiding the binding after it leaves the binder until it is substantially secured by the needle 8 of the stitching mechanism.

The operation of my device will be apparent from the above description. The binding strip is led through the binding strip guide and thence through the binder. The two edges of the fabric to be joined are directed through the folder and guide which folds the upper edge underneath and between the two overlapped edges, while the under edge of the fabric is left plain or unfolded. The binding strip is wrapped around this plain or unfolded edge and the needles of the stitching mechanism passing down through the overlapped edges secure the same together, as above described. After

the tubular article has been stitched, the presser foot may be raised and the article slipped off from the work-supporting arm.

While I have shown and described my invention as applied to a sewing machine for stitching tubular articles, it will be understood from certain aspects of the invention that the combined folding and binding mechanism may be used in connection with separate fabric sections for joining the edges thereof.

It will also be obvious that minor changes in the details of construction and arrangement of parts may be made, without departing from the spirit of the invention as set forth in the appended claims.

Having thus described my invention, what I claim as new and desire to secure by Letters Patent, is:

1. The combination with a tubular work support and stitch forming mechanism, of a folder for directing two overlapping edges to the stitching mechanism without folding the under edge, a binder for directing a binding strip about said unfolded edge of the fabric and a binding strip guide extending substantially parallel to the work supporting arm and disposed relative to said work supporting arm, so that a tubular article being stitched may extend about said binding strip guide.

2. The combination with a standard, a tubular work support, an overhanging arm, and stitch-forming mechanism including spaced needles mounted on said overhanging arm, of a folder for folding one only of two opposed overlapped edges, a binder for directing a binding strip about the plain or unfolded edge of the fabric, and a binding strip guide extending substantially parallel to the tubular work supporting arm from the rear of the machine for directing a binding strip to the binder.

3. The combination with a standard, a tubular work supporting arm carried thereby, an overhanging arm, and stitch-forming mechanism including spaced needles carried by the overhanging arm, of a slide movable longitudinally of the work support in front of said needles, a guide mounted on said slide and a binder disposed between said guide and the needles whereby one of the edges of fabric passing through the guide will be bound.

4. The combination with a standard, a tubular work-supporting arm carried thereby, an overhanging arm, and stitch-forming mechanism including spaced needles carried by the overhanging arm, of a slide movable longitudinally of the work support, a folder mounted on said slide, a binder disposed between said folder and the needles, whereby one of the edges of fabric passing through the folder may be bound, and a binding strip guide extending from a point adja-

cent the binder to a point at the rear of the machine for guiding a binding strip to the binder.

5. The combination of a standard, a tubular work-supporting arm carried thereby, an overhanging arm carried by the standard, stitch forming mechanism including needles mounted on the overhanging arm, a feeding mechanism for feeding the material onto 10 the work supporting arm, a folder located in front of the needles, said folder being shaped to fold the upper of two overlapped fabric edges and to direct the under fabric edge without folding, a binder disposed 15 between the folder and the needles, said binder being disposed at right angles to the line of feed and constructed so as to fold the binding strip, turn the lower edge of the binding strip outwardly upon itself, invert 20 the binding strip and direct the same about the plain or unfolded fabric edge.

6. The combination of a standard, a tubular work-supporting arm carried thereby, an overhanging arm carried by the stand- 25 ard, stitch forming mechanism including

needles mounted on the overhanging arm, a feeding mechanism for feeding the material onto the work supporting arm, a folder located in front of the needles, said folder being shaped to fold the upper of two overlapped fabric edges and to direct the under fabric edge without folding, a binder disposed between the folder and the needles, said binder being disposed at right angles to the line of feed and constructed 30 so as to fold the binding strip, turn the lower edge of the binding strip outwardly upon itself, invert the binding strip and direct the same about the plain or unfolded fabric edge, and a binding strip guide 35 extending from a point adjacent the binder parallel with the work supporting arm to a point at the rear of the machine for guiding a binding strip to the binder.

In testimony whereof, I affix my signature 40 in the presence of two witnesses.

ISIDOR FARER.
